UNITED STATES PATENT OFFICE

2,412,352

TEMPORARY SUPPORT FOR ARTIFICIAL TEETH

Simon Myerson, Brookline, Mass.

Original application August 26, 1940, Serial No. 354,205. Divided and this application April 7, 1943, Serial No. 482,110

13 Claims. (Cl. 32—71)

1

This invention pertains to dentistry and relates more particularly to a temporary supporting device for artificial teeth, designed for use in observing the effect of such teeth in a person's mouth before the teeth are permanently fixed in a denture—the present application being a division of the copending application of Simon Myerson, Serial No. 354,205, filed August 26, 1940, which is a continuation-in-part of the copending application of Simon Myerson, Serial No. 313,077, for Tooth holder, filed January 9, 1940. In said latter application there is disclosed a tooth holder designed temporarily to hold a group of artificial teeth, for example, six anterior teeth, in a manner such as in a general way to simulate the appearance of teeth permanently mounted in a denture or in the natural gum, and, at the same time, to constitute a practical shipping card for transmission of the teeth to the dental laboratory or dentist, as well as to constitute an acceptable mount for displaying the teeth for ready observation. Said latter application also discloses, broadly, certain forms of attaching devices operative temporarily to support the holder, with its complement of teeth, within the patient's mouth so that the dentist may observe the teeth, if desired, from a distance.

The present invention relates more especially to such supporting or attaching means, one object of the invention being the provision of a supporting appliance including means operative temporarily to secure the holder to another part, for instance to the roof of a person's mouth.

Other and further objects and advantages of the invention will be made manifest in the following more detailed description and by reference to the accompanying drawing in which

Fig. 1 is a front elevation of the tooth holder such as may be supported by the attaching means of the present invention, showing six anterior teeth mounted therein;

Fig. 2 is a section on the line 2—2 of Fig. 1;

Fig. 3 is a plan view of the device shown in Fig. 1;

Fig. 4 is a diagrammatic side elevation showing the tooth holder of the present invention mounted upon a desirable form of attaching means and arranged in position for observation within a patient's mouth;

Fig. 5 is a plan view, to larger scale, of the attaching means whereby the tooth holder is so held in position in the mouth;

Fig. 6 is an elevation, partly in section, on the line 6—6 of Fig. 5;

Fig. 7 is a section on the line 7—7 of Fig. 5;

2

Fig. 8 is a view similar to Fig. 7 but illustrating a modified construction;

Fig. 9 is a front elevation of the suction-cup supporting member of Fig. 6, the cup being broken away;

Fig. 10 is a view similar to Fig. 2, but showing a modification;

Fig. 11 is a side elevation, partly in vertical section, illustrating an appliance specifically designed to support a single artificial tooth for observation;

Fig. 12 is a perspective view, to large scale, showing details of the supporting appliance illustrated in Fig. 11;

Fig. 13 is a plan view similar to Fig. 3 but illustrating a modification;

Fig. 14 is a view similar to Fig. 11, but showing a holder like that of Fig. 1.

Referring to the drawing, the numeral 1 designates a novel and desirable tooth-holding device of the kind disclosed in the above-named application of Simon Myerson. This tooth holder 1 may be made of any suitable material, for instance hard rubber or gum-colored metal and may comprise one or more parts, but the preferred construction consists of an integral mass of a synthetic resin. Resins derived from methacrylic acid have been found particularly desirable for dental work.

As more particularly illustrated, by way of example, in Figs. 2 and 3, this holder is curved in horizontal section substantially like the human gum ridge and comprises the rear portion 2 and a front portion or apron 3.

While the holder is here shown as curved, a straight or concave holder (otherwise like that illustrated) is useful as a support for teeth during shipment. The rear and front portions, 2 and 3 respectively, are integrally joined at the upper edge 4 of the holder, said upper edge being properly shaped to fit between the gum ridge and the inner surface of the patient's lip. The parts 2 and 3 diverge downwardly from the upper part of the holder, thereby providing a socket cavity 45 which may be a single elongate horizontal groove extending from one end to the other of the holder, or, if preferred, this groove may be divided to form a plurality of independent sockets.

When hereinafter reference is made to this feature of the device, it should be understood that the term "socket" or "chamber" is intended to designate either a single groove for the reception of a series of teeth or to indicate an arrangement in which independent sockets for the several teeth are employed. This socket, cavity,

Fig. 7 is a section on the line 7—7 of Fig. 5;

Fig. 8 is a view similar to Fig. 7 but illustrating a modified construction;

3

chamber or groove is designed to receive tooth-attaching means, for instance a body 5 of dental wax (usually thermoplastic) into which the gingival ends of the teeth 7 may be pressed so that the teeth will be held removably in desired position within the holder by the retaining action of this wax. Preferably the socket chamber is of such dimensions as will permit the body of wax to embed the usual attaching pins 6 of the teeth so as thereby to furnish a very secure anchorage. As here illustrated, the teeth are of a novel and improved type wherein the incisal portion is of relatively greater transparency than the upper or body portion, and in which stria-simulating inserts, and in some instances simulated fillings, are incorporated.

The teeth 7 are mounted, as just stated, with their gingival portions sunk or embedded in the body 5 of wax in the socket chamber, and in order to simulate the appearance of the human gum, the front surface of the gum-simulating part or apron 3 is properly colored and configured, and has its lower part tapered downwardly and provided with a plurality of arcuate recesses for the reception of the necks of the individual teeth. The portions of the apron which separate these recesses form cusps 9 which intervene between adjacent teeth. Preferably the wax 5 is of a thermoplastic character such that it may be softened by the application of heat and when allowed to cool hardens again. Thus the teeth may be embedded in the wax while the latter is soft and become firmly fixed in the holder when the wax hardens, although they may be removed individually when desired.

The holder 1 has a rearwardly extending integral lug or boss 10 which, as illustrated in Figs. 2 and 3, is furnished with an opening or slot 11 for the reception of an attaching key or pin as disclosed in application Serial No. 354,205, the lug 10 also constituting means for engagement by a clamping device forming part of the novel supporting appliance or attaching means now to be described.

Referring to Figs. 5, 6, 7 and 9, this attaching means comprises a clamping block 12 having extending therethrough a socket opening or guideway 13 into which the lug 10 of the holder may be slid. As shown in Figs. 2 and 7, the lug and the socket opening 13 are of substantially rectangular contour so that when the lug is fitted in the opening the holder cannot tip sidewise. The block 12 is furnished with a transverse passage intersecting the opening 13 and in which is disposed a pivot pin 14. This pivot pin may be arranged loosely in the passage or it may be of flexible material and is engaged at its central part by a clamping screw 15 having a knurled head H. This clamping screw 15 engages a screw-threaded opening in the block 12 and when it is turned, it may be caused to bear against the center part of the pin 14 so as to cramp the latter against the lug 10 and thus secure the holder to the block 12 and at the same time, prevent the block 12 from turning about the pin 14 as a pivot. The pin 14 projects beyond the opposite sides of the block 12 and to its opposite ends 16 and 17 are secured the forward ends of a pair of wire rods 18 and 19 (Fig. 5), respectively, constituting elements of a bracket by means of which the block 12 may be attached to a support. The members 18 and 19 project rearwardly and comprise substantially parallel portions 20 and 21 whose rear ends pass freely through openings in the wall of a substantially cylindrical cup-

4

support 22 (Fig. 6). This cup support is elongate and tubular and closed at one end. The support 22 is provided with an external boss 23 upon which is mounted a suction cup 24 of soft rubber or the like which is designed to engage an inner surface of the patient's mouth, for example, the mucous membrane of the hard palate indicated at 25 in Fig. 4. When the parts are thus disposed, the gum ridge 26 fits closely against the rear surface of the rear part 2 of the holder 1.

Within the tubular cup-support 22 there are arranged three loose pins 27, 28 and 29, respectively, (Fig. 6). The opposed ends of adjacent pins are shaped to provide pairs of clamping jaws between which are disposed the parts 20 and 21, respectively. The pin 29 projects beyond the open end of the support 22 and its outer end 30 engages the inner surface of a screw-threaded cap 31, which is screwed onto the end of the support 22. When the cap 31 is partly unscrewed it leaves the pins 27, 28 and 29 free to separate, thus permitting the rods 20 and 21 to slide freely with reference to the support 22. The openings in the wall 22 through which the rods 20 and 21 pass are elongate circumferentially of the support (Fig. 9) so that the support may pivot about the axis provided by the pins 27, 28 and 29, said axis extending substantially horizontally and transversely of the mouth when the device is in use. In the same way, the block 12 is free to pivot about the pin 14 when the clamping screw 15 is loosened. Moreover, when screw 15 is loosened the boss 10 may be adjusted longitudinally within the opening 13. The tightening of the screw 15 locks the block 12 both against pivoting and against sliding on the boss 10. Obviously, ball-and-socket joints may be substituted for the connections herein specifically illustrated, whereby the bracket is adjustably united to the holder and/or the cup-support, respectively.

In Fig. 8 a modified arrangement is shown wherein the boss 10^a of the tooth holder is of circular transverse section instead of rectangular. The opening in the block 12^a, which receives the boss 10^a, is curved in contour but in other respects the arrangement is generally similar to that of Fig. 7, and when the clamping screw 15^a is tightened, the block is prevented from pivoting on the block 14, and the boss 10^a of the holder is prevented from sliding in the block.

When the holder 1 is secured to the supporting or attaching means illustrated in Figs. 5 to 9, it may be placed in the patient's mouth and temporarily suspended and firmly held in place by the attaching means including the suction cup 24. By reason of the several adjustments provided, the holder may be disposed at the proper position in the mouth regardless of the size of the mouth or the position of the gum ridge, and without distorting the lips, and when so arranged the teeth may be observed by the dentist and by the patient with the aid of a mirror, from a distance if desired. The dentist and patient may thus obtain an accurate idea of the appearance that the teeth would have if permanently mounted in a denture. Since the teeth 7 are removably secured in the holder 1, it is possible (if the dentist does not like the appearance of the teeth when first tried in the patient's mouth) to remove the entire holder and substitute another having a differing set of teeth, or he may remove individual teeth from a holder and replace them with other teeth, or rearrange them in the holder so as to obtain

the most desirable effects and those most closely resembling the appearance of the patient's own natural teeth. When the dentist has thus determined, by trial, the form, color and size of tooth which gives the best effects and how they should be best arranged, he may then employ the assemblage which has thus been found to give the best result, in making up the denture in which may be permanently fixed the same teeth which have been tried and found satisfactory when arranged in the holder.

As illustrated in Figs. 11 and 12, a single tooth T is arranged with its pin or pins 6 embedded in a mass of wax 5 within a socket cavity in a part 10^z (preferably a horizontally flattened tube) having secured thereto an attaching bracket 10^x to which is fixed the suction cup 24^x by means of which the appliance may be temporarily held in the mouth. Instead of filling the part 10^z with wax for the reception of the pins of a single tooth, the part 10^z may be made of such dimensions (Fig. 14) as to receive the lug 10 of the holder 1, preferably with a sliding fit, so that the holder may be adjusted longitudinally of the part 10^z. The arrangement of Fig. 15 thus provides a somewhat simpler type of support for the holder than that previously described.

In Fig. 10, the attaching lug 10^m is shown as a separate element, for instance a length of flexible metal, having one end embedded in the substance of the holder, its projecting portion being designed to be received in the socket of a bracket or such other supporting means as may be employed.

In Fig. 13 a further modified form of holder 1^x is illustrated, such holder being in general similar to the holder 1 above described but having extensions 40 reaching around to the molar region of the mouth, and which may constitute supports for molar teeth 42 and also for elongate suction cups 43 designed to engage the molar region of the gum and thus to afford additional attaching means for temporarily retaining the holder in the mouth.

While as herein specifically illustrated by way of example, the teeth are shown as upper teeth, and in describing the teeth and holder, such terms as "upper" and "lower" may have been used, it is to be understood that all such expressions have been employed merely for convenience in description and without limiting intent, and that the appliance herein claimed is intended for use with lower teeth as well as for use with upper teeth.

While certain desirable embodiments of the invention have herein been illustrated and described, it is to be understood that the invention is not necessarily limited to these particular embodiments, but is to be regarded as broadly inclusive of all modified constructions, substitutions of material, and variation in arrangement of parts which fall within the scope of the annexed claims.

I claim:

1. An appliance for temporarily supporting a tooth display holder within the mouth, said appliance comprising substantially rigid parts which are relatively adjustable for properly locating the holder both up and down and from front and rear, one of said parts being designed and arranged for attachment to the holder, and another of said parts being provided with means operative, independently of the relative position of the jaws, temporarily to affix said latter part to an inner surface of the mouth, and means operative to fix

said parts in chosen relative position of adjustment.

2. An appliance for temporarily supporting a display holder for artificial teeth within the mouth, said appliance comprising relatively movable, substantially rigid parts whereby the holder may be adjustably and properly positioned either up or down or from front to rear, means for fixing said relatively movable parts in chosen position of adjustment, and an attaching element, spaced rearwardly and posteriorly of the holder, engageable with an inner surface of the mouth and operative, independently of the position of the opposing jaw, to suspend the entire appliance together with the holder from the intra-oral surface.

3. An appliance for temporarily supporting artificial teeth in the mouth for observation, the appliance being constructed and arranged to be located wholly within the oral cavity and temporarily to position tooth-holding means within the mouth thereby to permit observation, between the parted lips, of a tooth or teeth carried by the holding means, the appliance comprising a clamp comprising relatively movable parts operative releasably to engage between them a part of the tooth-holding means, a suction cup, a bracket connecting the cup and clamp, and means adjustably uniting the bracket to the cup.

30 4. A support for dental use, said support comprising a clamp engageable with a part to be supported in the mouth, a suction cup, a bracket connecting the clamp and cup, the bracket being pivotally connected both to the cup and clamp, the clamp comprising a single locking element operative concomitantly to secure said part to the clamp and to fix the clamp against rotational movement relative to the bracket.

5. A support for dental use, said support comprising a clamp engageable with a part to be supported in the mouth, a suction cup, a bracket connecting the clamp and cup, means uniting the cup to the bracket, said latter means including a guide in which a part of the bracket may slide, and means operative concomitantly to secure the bracket against sliding or rotative movement with reference to the cup.

6. A support for dental use, said support comprising a clamp, a suction cup and a bracket, a pivot pin uniting the bracket and clamp, the clamp having therein a socket, one wall of which is constituted by said pivot pin, said socket being designed for the reception of a part which is to be supported in the mouth, and a clamping screw operative to press the pivot pin against said part thereby concomitantly to fix said part within the socket and to prevent movement of the clamp relative to the bracket.

7. A support for dental use, said support comprising a clamp, a suction cup and a bracket, means uniting the clamp and the bracket, and parts uniting the cup to the bracket, said latter parts including pivot means defining an axis, extending transversely of the mouth when the support is in use, about which the bracket may swing, and means operative to prevent relative movement of the cup and bracket about the axis of said pivot means.

70 8. A support for dental use, said support comprising a clamp, a suction cup and a bracket, means uniting the clamp and bracket, and elements uniting the cup and bracket, said elements including means providing a guide in which the bracket may slide, and means operative to pre-

vent movement of the bracket relatively to said guide.

9. A support for dental use, said support comprising a clamp, a suction cup and a bracket, means uniting the clamp and bracket, parts uniting the cup and bracket, said latter parts including a tubular housing fixed to the cup, said housing having guide openings for the bracket whereby the bracket may be slid relatively to the housing, and means within the housing for clamping the bracket against movement relative thereto.

10. A support for dental use, said support comprising a clamp, a suction cup and a bracket, means uniting the clamp and bracket, parts uniting the cup and the bracket, said latter parts including a tubular housing fixed to the cup, the housing having guide means for the bracket, said guide means being so constructed and arranged that the housing may be rotated relative to the bracket as well as slid longitudinally of the latter, locking means within the housing operative to prevent relative movement of the housing and bracket, and means for actuating said locking means.

11. An appliance for temporarily supporting artificial teeth in the mouth for observation, said appliance including a part constructed and arranged for adhesive attachment to an intra-oral surface, a rigid part having therein a socket for the reception of tooth-holding means, said socket opening forwardly, and substantially rigid uniting means connecting said parts in spaced relation, the appliance being so constructed and arranged as to permit front-to-rear relative man-

ual adjustment to a predetermined degree of the tooth-holding means and said attaching part.

12. An appliance for temporarily supporting artificial teeth in the mouth for observation, said appliance including a holder of normally substantially rigid and shape-retaining material, the holder having a cavity for the reception of plastic material operative removably to secure teeth to the holder, the holder having an elongate attaching lug projecting from its lingual side, a part having therein a socket cavity which receives the lug of the holder with a sliding fit whereby the holder may be adjusted relatively to said socketed part, an element designed for adhesive attachment to an intra-oral support, and a bracket uniting said attaching element to the socketed part.

13. An appliance for temporarily supporting artificial teeth in the mouth for observation, said appliance including a holder of normally substantially rigid and shape-retaining material, the holder having a cavity for the reception of plastic material operative removably to secure teeth to the holder, the holder having an attaching lug projecting from its lingual side, and a support including a length of tubing having its axis substantially horizontal, the tubing being of such transverse internal dimensions and contour as to receive the lug of the holder with a sliding fit, a bracket secured to the length of tubing, and a suction cup attached to the bracket whereby the entire appliance may be removably attached to a surface of the mouth.
